POST ACCELERATION GRID DEVICES

Charles Dufour, Paris, France, assignor to Compagnie Générale de Télégraphie Sans Fil, a corporation of France

Application December 1, 1955, Serial No. 550,413

Claims priority, application France December 2, 1954

2 Claims. (Cl. 315—14)

The present invention relates to post acceleration grid devices for oscilloscopes and other tubes, such as the Graphecon. A device of this type has been described in the co-pending application Serial No. 497,311 filed on March 28, 1955, now abandoned, by Charles Dufour for: Improvements in Oscilloscopes Systems. It comprises a thin grid of high transparency, positioned at a small distance from the tube target (for instance 5 to 30 mm.) and subjected to a low voltage with respect to the anode voltage of 10,000 volts. It can be proved that such a device will not introduce any geometrical distortion into the system, while operating with a much higher sensitivity than that of conventional post-accelerating cathode-ray tubes. The device has, however, the following disadvantages: the impact of the electrons on the post-accelerating grid extracts secondary electrons, a certain number of which, in oscilloscopes for instance, are picked up by the screen which is the seat of a much higher potential than that of the grid. An electron in the beam will then produce a small luminous patch on the screen, instead of a luminous point, causing the curves or images represented to be slightly blurred. It has been thought possible to avoid the blurring effect by increasing the transparency of the grid or by reducing the number of meshes. The results of these experiments, however, were unsatisfactory.

The object of the invention is a post-accelerating grid device usable in oscilloscopes or other tubes which does not present this disadvantage.

The device according to the invention comprises a post-accelerating grid and a second grid placed between the post-accelerating grid and the target, said second grid being spaced from said post-accelerating grid by a distance which is small with respect to its distance from the target, said second grid being impressed with a voltage slightly lower than that of the first grid.

According to one feature of the invention, the wires of one of the grids are inclined at an angle of 45° with respect to the wires of the other grid.

According to another feature of the invention, the two grids form a single unit comprising a grid-shaped insulating support having a metal film coated on either side thus forming first and second grids.

The invention will be better understood with the aid of the appended description and with reference to the annexed drawings, wherein:

Fig. 1 shows a diagram of a cathode ray tube embodying the post-accelerating device according to the invention.

Fig. 2 is an explanatory diagram of operation of the tube of Fig. 1.

Fig. 3 shows the preferred relative position of the meshes of the two grids.

Fig. 4 shows a cross-sectional view of a detail of a preferred embodiment of the post-accelerating device according to the invention.

In Fig. 1, the cathode ray tube represented comprises a glass envelope 1, coated with a metal film 2 raised to

2

a voltage of 1500 volts with respect to the electron emissive cathode of gun 16 of the tube, the voltage of which being taken as the reference voltage. This metal film is connected to a thin grid of high transparency termed "post-accelerating grid" 3, positioned at a distance of about 20 to 30 mm. from a target or screen 4. Said screen 4 is coated with an aluminum film and raised to a potential of 11,500 volts. According to the invention, a second grid 5, termed "screen-grid," is located between grid 3 and screen 4 at a distance of about 10 mm. from grid 3. This screen grid 5 is raised to a voltage of 1,000 volts, i. e. at -500 volts with respect to grid 3. Grids 3 and 5 are very thin and comprise 20 square meshes per mm. Besides these elements, the tube according to the invention comprises all other parts common to conventional cathode-ray tubes, i. e.: the above-mentioned electron gun 16 with focusing and accelerating electrodes (not shown), and horizontal and vertical deflecting plates 6, 7 and 8, 9. A direct current source 10 provides the necessary voltages required by the various elements.

The cathode-ray tube of Fig. 1 operates as follows (for a better understanding of the operation, Figure 2 has been drawn on a larger scale):

Screen 4, post-accelerating grid 3 and screen grid 5 are, as mentioned, raised to a voltage of 11,500, 1,500 and 1,000 volts, respectively. The trajectory of a primary electron emitted by gun 16 appears at points 11, 13 and 15 of grids 3 and 5 and screen 4 respectively; the trajectories of the secondary electrons generated by said electron through the impact on the two grids are shown at 11—12 and 13—14. The screen grid 5 will thus repel the secondary electrons leaving the post-accelerating grid 3 with zero initial velocity. These electrons will fall back on the latter grid 3. Also, said post-accelerating grid 3, close to screen grid 5, will intercept the secondary electrons produced through the impact of the primary beam on the latter. No secondary electron will thus reach the screen and the post-acceleration process will not be substantially modified thereby.

A moiré or watered silk effect on the oscilloscope could eventually occur, were one of the grids to become slightly displaced with respect to the other, if the wires constituting the meshes of said two grids were parallel to one another. This is avoided by arranging the two grids in the manner shown in Figure 3, wherein one of the grids is represented in solid lines and the other in dotted lines, the wires of one of the grids being inclined at an angle of 45° with respect to the wires of the other grid.

Finally, grids 3 and 5 may also form a single unit as shown in cross-section in Figure 4: a grid-shaped support 17, made of insulating material, is mounted in the tube, perpendicular to the axis of gun 16, between the gun 16 and the screen 4. On the side of the support facing the gun, a film of conductive material is deposited, constituting grid 3. On the opposite side, a second film is deposited constituting grid 5.

Perfect parallelism between the grids 3 and 5 is thus insured. Any short-circuit resulting from the application of different potentials to said two grids and any shift of one of the grids with respect to the other are therefore avoided. These grids being rigorously parallel, the transparency of the grids is increased.

The tube described above gives valuable results; the resulting post-acceleration, while retaining its own advantages, does not introduce any blur into the image on the oscilloscope.

What I claim is:

1. A monochromatic cathode ray tube of the type including a cathode, a target, a post-accelerating grid disposed in the vicinity of said target, means for raising said post-accelerating grid to a potential slightly posi-

tive with respect to said cathode and highly negative with respect to said target, and means for causing an electron beam issued from said cathode to scan said target, said tube further comprising an additional grid disposed between said post-accelerating grid and said target, substantially nearer to the post-accelerating grid than to the target, and means for raising said additional grid to a slightly negative potential with respect to said post-accelerating grid, whereby secondary emission electrons from both grids are prevented from reaching said target, said grids being constituted of fine wires, the wires of said first grid being disposed at an angle of 45° with respect to the wires of said second grid.

2. A monochromatic cathode ray tube of the type including a cathode, a target, a post-accelerating grid disposed in the vicinity of said target, means for raising said post-accelerating grid to a potential slightly positive with respect to said cathode and highly negative with respect to said target, and means for causing an electron beam issued from said cathode to scan said target, said tube further comprising an additional grid disposed be-

15 tween said post-accelerating grid and said target, substantially nearer to the post-accelerating grid than to the target, and means for raising said additional grid to a slightly negative potential with respect to said post-accelerating grid, whereby secondary emission electrons from both grids are prevented from reaching said target, further comprising a grid-shaped insulating support having a first and a second sides, said first and second sides being respectively coated with a first and second films of metal constituting respectively said first and said second grids.
